UNITED STATES PATENT OFFICE.

FREDRICK H. GOSS, OF CORAOPOLIS, PENNSYLVANIA.

TELEPHONE-RECEIVER HOLDER.

1,002,360.

Specification of Letters Patent.

Patented July 9, 1912.

Application filed February 27, 1912. Serial No. 680,259.

To all whom it may concern:

Be it known that I, FREDRICK H. Goss, a citizen of the United States of America, residing at Coraopolis, in the county of Allegheny and State of Pennsylvania, have invented certain new and useful Improvements in Telephone-Receiver Holders, of which the following is a specification, reference being had therein to the accompanying drawing.

This invention relates to a telephone receiver holder, and the primary object of my invention is to furnish the transmitter arm of a telephone with positive and reliable means for supporting receivers in position to be used when the head is placed in proximity to the transmitter for talking purposes.

Another object of this invention is to provide a telephone with receivers that can be easily and quickly shifted into engagement with the ears, when the telephone is to be used, without resorting to the use of the hands, thereby permitting of a person talking over the telephone while using the hands for other purposes.

A further object of this invention is to provide a telephone receiver holder of novel construction that allows both ears to be used in receiving a message when carrying on a conversation over the telephone.

A still further object of this invention is to provide a receiver holder that is simple in construction, durable, applicable to various types of telephones and highly efficient for the purposes for which it is intended.

With the above and other objects in view, the invention resides in the novel construction, combination and arrangement of parts to be hereinafter specifically described and then claimed.

Reference will now be had to the drawing, wherein:—

Figure 1 is a side elevation of a telephone receiver holder in accordance with this invention, and Fig. 2 is a plan of the same.

The reference numeral 1 denotes a portion of a transmitter arm having a transmitter 2, and attached to said arm by a clamping screw 3 is the lower bifurcated end 4 of an upright 5. The upper end of the upright 5 is bifurcated, as at 6 and adjustably mounted in the upper end of said upright by a clamping screw 7 is the rearward extension 8 of a frame 9 that has parallel arms 10 and inwardly projecting supports 11.

Pivots connected to the supports 11 by pins 12 are receiver holders 13, said holders having the forward ends thereof provided with oppositely disposed receivers 14. These receivers have binding posts 15 to which wires of a telephone circuit are connected. The holders 13 are carried by the lower end of the pins 12 and mounted upon the upper ends of said pins are cranks 16 that are pivotally connected by pins 17 to links 18, said links being pivotally connected by pins 19 to a curved head piece 20 that has a pad 21.

Mounted in the arms 10 are the outer ends of curved pins 22, said curved pins extending into apertured depending lugs 23 carried by the cranks 16. Encircling the curved pins 22, between the arms 10 and the lugs 23, are coiled compression springs 24, said springs retaining the receivers 14 in an open position, whereby a head can be easily placed in engagement with the pad 21 of the head piece 20.

Wires 25 connect the binding posts 15 to contact pieces 26, carried by the cranks 16, and these contact pieces are adapted to contact with L-shaped contact pieces 27, carried by the inner sides of the arms 10, the contact pieces 27 being shifted to extend into the path of the contact pieces 26 when the cranks 16 are shifted. The contact pieces 27 are connected to telephonic circuit wires 28, heretofore referred to.

When it is desired to use the telephone, it is only necessary to place the forehead of the head in engagement with the pad 21 of the head piece 20 and by a slight pressure upon said head piece, the receivers 14 are shifted into engagement with the ears and the contact pieces 26 into engagement with the contact pieces 27, thereby establishing a telephonic circuit that permits of a conversation being carried on through the medium of the transmitter 2.

It is apparent that the frame 9 can be adjusted to correctly position the receivers 14 relatively to the transmitter 2 and that the natural position of the head in front of the transmitter 2 for talking purposes will correctly position the receivers 14 for hearing purposes. Immediately upon the head being removed from the head piece, the telephonic circuit is broken and the receivers 14 are moved a sufficient distance apart to permit of the head being moved away from the telephone without injury to the receiver holders.

It is thought that the operation and utility of the device will be apparent without further description, and while in the drawing there is illustrated a preferred embodiment of the invention, it is to be understood that the structural elements thereof are susceptible to such changes as fall within the scope of the appended claims.

What I claim is:—

- 10 1. In a telephone receiver holder, the combination with a transmitter arm, of a frame adjustably supported thereby, oppositely disposed receiver holders movably supported by said frame and supporting receivers, a head piece in connection with said holders and adapted to be pressed to adjust said holders, and contact pieces in connection with said frame and adapted to establish a telephonic circuit when said head piece is pressed.
- 15 2. The combination with a transmitter arm, of a frame adjustably supported thereby, inwardly projecting oppositely disposed supports carried by said frame, receiver holders pivotally carried by said supports, cranks movable with said holders, a head piece loosely connected to said cranks and adapted to be pressed to adjust said receiver holders, and contact pieces carried by said cranks and said frame for establishing a telephonic circuit when said head piece is pressed.
- 20 3. The combination with a transmitter arm, of a frame adjustably supported thereby, inwardly projecting oppositely disposed supports carried by said frame, receiver holders pivotally carried by said supports, cranks movable with said holders, a head piece loosely connected to said cranks and adapted to be pressed to adjust said receiver holders, contact pieces carried by said cranks and said frame for establishing a telephonic circuit when said head piece is pressed, and means in connection with said frame and

said cranks for retaining said receiver 45 holders in a normally open position.

4. In a telephone receiver holder, the combination with a transmitter arm, of an upright clamped thereto, a frame adjustably supported by said upright, oppositely disposed supports carried by said frame, receiver holders pivotally connected to said supports, cranks movable with said receiver holders, a head piece loosely connected to said cranks and adapted to be pressed to move said holders, contact pieces supported by said cranks and said frame and adapted to establish a telephonic circuit in connection with the receivers of said holders, and spring interposed between said cranks and 60 said frame and adapted to retain said holders in a normally open position.

5. In a telephone receiver holder, the combination with a transmitter arm, of an upright clamped thereto, a frame adjustably 65 connected to said upright, oppositely disposed supports carried by said frame, holders pivotally carried by said supports, receivers carried by said holders, cranks movable with said holders, a curved head 70 piece loosely connected to said cranks and adapted to be pressed to move said holders, contact pieces carried by said cranks and electrically connected to said receivers, contact pieces carried by said frame and adapted to be engaged by the first mentioned contact pieces to establish a telephonic circuit in connection with said receivers, and means interposed between said cranks and said frame for holding said receiver holders in 80 a normally open position.

In testimony whereof I affix my signature in the presence of two witnesses.

FREDRICK H. GOSS.
